UNITED STATES PATENT OFFICE.

HENRY A. BROWN AND JAMES WILEY, OF BROOKLYN, NEW YORK.

IMPROVED FOUNTAIN-PEN.

Specification forming part of Letters Patent No. 14,276, dated February 19, 1856.

To all whom it may concern:

Be it known that we, HENRY A. BROWN and JAMES WILEY, of Brooklyn, Kings county, State of New York, have invented certain Improvements in Fountain-Pens; and we do hereby declare the following to be a full description of the same.

We are aware that fountain-pens have been made before this of our invention, and therefore do not set up any claim to have invented the first fountain-pen.

Our invention relates to the mode of constructing the pen and combining it with the pen-holder and case, so as to hold the ink under all circumstances and at the same time control its flow when being used.

In all other fountain-pens known to us there is either great complexity of arrangements to effect these results, thereby making it liable to get out of repair, or there is a constant tendency to too great flow of the ink, and thereby causing the paper to blot while writing, or the pen-holder case always has to be held in an inverted position to prevent the escape of ink, and thereby confining or limiting the use of such fountain-pens to the desk, and not making them portable and of universal use, as they should be, unless at the great risk of inking or soiling clothes if attempted to be carried in the pocket. Our invention, therefore, is to obviate these several objections found to exist in the various fountain-pens that have been made and attempted to be put in public use. To do this we have made the concave shank of the pen with a solid head and combined it with the pen-holder, having a valve-seat in it, in such a way that by sliding the pen out or in—that is, shortening or elongating the nib of the pen in the pen-holder—it acts as a slide-valve against the valve-seat in the pen-holder to cut off the flow of ink, except when the pen is in use, while at all other times the ink is securely confined in the barrel of the pen-case, and may be carried in the pocket or otherwise laid down without risk of leakage; but to describe our invention more particularly we will refer to the accompanying drawings, forming a part of this specification, the same letters of reference wherever they occur referring to like parts.

Figure 1 is a perspective view of the pen

and case. Fig. 2 is a vertical cut section of the same, showing the piston for charging the case with the ink. Figs. 3, 4, and 5 are representations of sections of the case as made before putting together. Fig. 6 is a representation (in section) of the pen and pen-holder, showing the solid head elevated or raised from its valve-seat, formed in the neck of the pen-holder.

Letter A represents the pen, having a solid head B. This is formed by filling the concave of the shank of the pen with a suitable piece of metal, so as to form a half-circular head. To the lower edge of this head is secured a twisted wire C, having a split lower end and overlapping the split of the pen. The object of this twisted wire is to convey the ink to the nib of the pen and at the same time, in consequence of its twist, prevent the too rapid flow of the ink.

Letter D is the pen-holder, which is made by cutting away about one-half of the length of the holder and facing the part cut away with a plate E, for the purpose of forming, by the transverse cut or notch in the pen-holder, a seat for the head or valve B to act against to cut off the flow of ink from the barrel to the pen, and by its elongated lower edge e², extending down into the concave of the shank of the pen, acting at the same time as an ink-distributer—that is, the sides of the distributor e² are not attached to the pen-holder, nor do they fit tightly the sides of the concavity of the shank of the pen, but have a space between them, and the lower end forked so as to straddle the twisted wire. The object of this construction of the distributor is to allow of the action of the atmosphere against the sides of the base of the column of ink, so as to cause it to flow down the twisted wire, but not acting upon any large portion of the ink. Of course only a limited supply is obtained, just equal to the wants of the writer using the pen.

Letter F is the barrel or fountain of the pen. Into the lower end of this is secured the pen-holder and pen. Into this barrel is adjusted a piston G and rod g², attached thereto. The object of this piston is to charge the fountain or barrel with ink. This is done by raising the valve B from off its seat in the pen-holder and inserting the pen into a bot-

tle of ink and then drawing back the piston by the common and well-known operation of filling syringes, &c.

Letter H is a ferrule for protecting the upper end of the piston-rod by fitting upon the end of the barrel, and J is another ferrule for protecting the pen-point, also fitting upon the lower end of the barrel.

Having now described our invention and its operation, we will proceed to state what we claim and desire to secure by Letters Patent of the United States.

What we claim is—

The making of the pen A with a solid half-circular head B and arranging it to slide in the pen-holder, (having a face-plate E and e^2 , as set forth,) so as to operate as a slide-valve or cut-off to the flow of ink, when operated substantially as hereinbefore set forth, and in form and manner and for the purposes described.

HENRY A. BROWN.
JAMES WILEY.
